CLAIM

The ornamental design for a ceiling fan controller as shown and described.

DESCRIPTION

FIG. 1 is a perspective view of a ceiling fan controller showing my new design;

FIG. 2 is a front elevation view thereof;

FIG. 3 is a rear elevation view thereof;

FIG. 4 is left side view thereof;

FIG. 5 is right side view thereof;

FIG. 6 is a top plan view thereof;

FIG. 7 is a bottom plan view thereof; and,

FIG. 8 is a perspective view thereof from another angle.

The structure shown in broken line is illustrative of environment and forms no part of the claimed design.

1 Claim, 8 Drawing Sheets
